DESIGN FOR A SHOE ORNAMENT

Margaret Mann Cameron, New York, N. Y.

Application July 27, 1945, Serial No. 121,016

Term of patent 3½ years

(Cl. D7—6)

To all whom it may concern:

Be it known that I, Margaret Mann Cameron, a citizen of the United States, residing at New York city, in the county of New York and State of New York, have invented a new, original, and ornamental Design for a Shoe Ornament, of which the following is a specification, reference being had to the accompanying drawing, forming a part thereof.

I claim:

The ornamental design for a shoe ornament, as shown.

MARGARET MANN CAMERON.
